UNITED STATES PATENT OFFICE.

RAY L. HULL, OF SAN FRANCISCO, CALIFORNIA.

SPARK-PLUG.

1,388,343.

Specification of Letters Patent. Patented Aug. 23, 1921.

Application filed November 28, 1919. Serial No. 341,188.

To all whom it may concern:

Be it known that I, RAY L. HULL, a citizen of the United States, and a resident of the city and county of San Francisco, State 5 of California, have made a new and useful invention—to wit, Improvements in Spark-Plugs; and I do hereby declare the following to be a full, clear, concise, and exact description of the same.—

10 This invention relates particularly to a modified form of spark plug for internal combustion engines.

The principle object of this invention is to reduce the exposed area of porcelain within 15 the cylinder and expose it to the immediate action of the spark upon which carbon and the waste products of combustion can be deposited.

It is a further object that the porcelain 20 may be removed from the retaining shell without removing the shell from its position in the cylinder wall.

Another object contemplates a construction and arrangement of parts whereby the 25 porcelain and insulating block may be spaced away from the retaining shell to allow for expansion and contraction, as well as to provide a more perfect insulation.

A still further object resides in providing 30 a plug which is simple and inexpensive to manufacture, efficient and durable in use.

In this specification and the annexed drawings, the invention is disclosed in the form considered to be the best, but it is to be 35 understood that the invention is not limited to such form, because it may be embodied in other forms, and it is also to be understood that in and by the claim following the description it is desired to cover the invention 40 in whatever form it may be embodied.

In the accompanying one sheet of drawing:

Figure 1 is a side elevation of my improved spark plug shown in the wall of an 45 internal combustion engine.

Fig. 2 is vertical section through the plug taken on the line II—II of Fig. 1.

Fig. 3 is a side elevation of the plug removed from the base shell.

50 Fig. 4 is an elevation of the insulating element and electrode.

Fig. 5 is a plan view of the bottom of the plug assembled.

In detail the construction illustrated in 55 the drawings includes the outer base shell 1 of the spark plug comprising a cylindrical

body of metal, with a hexagonal portion to provide a grip for a wrench, and having a contracted, externally threaded, tubular stem 2 at one end thereof, adapted to engage 60 the spark plug socket of an internal combustion engine. The shell 1 is threaded internally, as at 4 at its outer end and has the annular internal flange 5 formed at its inner end.

65 The retaining shell comprises a hollow cylindrical shell 6 having an enlarged, hexagonal flange 7 on one end thereof for wrench engagement. Adjacent said flange, the shell 6 is exteriorly threaded at 8 to 70 engage the internally threaded portion 4 of the outer shell 1.

The insulation member 9 consists of a cylindrical element preferably of porcelain, having a reduced end as at 10, leaving the 75 shoulder 11. The porcelain 9 is secured within the cylindrical shell 6 by interposing the annular flanged bushing 12 between the wall of the shell 6 and the body of the porcelain 9 both of which it frictionally engages.

The annular, internally projecting flange 5 on the bushing engages the shoulder 11. The asbestos or other heat resisting gasket 12, interposed between the flange 5 and the shoulder 11 permits expansion and prevents shocks or strains being transmitted to the porcelain liable to cause breakage.

The conducting rod 14 is concentrically located within the porcelain 9 and has the star shaped firing electrode 15 welded or fixedly 80 secured thereon. The opposite end of the rod 14 projects beyond the porcelain and through the conical cap 16 of the refractory material, engaging the tapered end 17, formed on the porcelain 9. The cap 16 centers the porcelain 9 within the shell 6 by resting in the annular depression 18 turned in the upper face of the flange 7.

The porcelain 9 is rigidly positioned on the rod 14 by adjusting the lock nut 19 on the threaded end thereof, against the washer 20 and forcing the porcelain snugly against the fixed firing point 15. The binding nut 21 adjacent the lock nut 19 serves to bind the terminal wire running to the switch control, 85 not shown.

The shell 6, with porcelain 9 secured therein, is assembled in the base 1 by engagement of the external threads provided on the shell 6 with the internal threads 4 of the outer shell 1. The reduced end 10 of the porcelain 9, with the star shaped firing points

thereon projecting beyond the end of the shell 6, extends through the central opening, provided in the end of the base 1, and the shoulder 11 thereon engages with the annular 5 internal flange 5, formed in the interior of the said hollow base 1. The flange 5 is tapered or beveled internally at 23' surrounding the electrode 15.

The reduced portion 10 of the porcelain 9 10 snugly engages the opening in the shell 6 through which it passes and the only exposed surface is between the points 23 of the electrode 15 and around the firing point where the flange 5 is chambered away at 23'.

15 The utility of such construction is strongly emphasized during the functioning period of the plug, when the intensified sparking area around the firing points generates such an intense heat that the waste products of combustion cannot be deposited upon any exposed surface behind the electrode 15, by reason of the barrier formed by the sparks traveling between the main and ground electrodes. It is practice to construct spark 20 plugs with the ground electrode spaced away from the porcelain body forming a "smoke hole" thus exposing a large surface to engine compression and deposits can collect with no disrupting action to destroy it.

25 Such deposits are detrimental to the efficient operation of the plug, since carbon deposits are better conductors than the air-gap between the main and ground electrodes.

30 The flat, star shaped, electrode point is positioned to lie substantially flush with the exposed end of base 1, so that if the plug is dropped the exposed parts, upon which it would strike, would be of such character as to be unbreakable. Many standard spark 35 plugs have so much of the porcelain exposed, that the slightest unusual jar causes a crack which necessitates discarding the porcelain. It is obvious in the improvement I have provided that loss by breakage is negligible 40 and thus a longer life of plug is assured.

In the present construction the exposed area of porcelain is reduced to the minimum consistent with good insulation; and is surrounded by a zone of electrical disturbance 50 reducing the tendency to carbon precipitation therein. Multiplication of the discharge points 23, in practice, has proved that the spark travels around from one position to another, because of varying electrical conditions, thus keeping all the points 55 burned clean, and creating an electrical zone of discharge between the terminals that has a disrupting effect upon carbon deposits before their mass can build up to a point of conductivity greater than the spark gap.

60 Having thus described my invention what I claim and desire to secure by Letters Patent is:—

A spark plug such as described comprising a hollow cylindrical base, externally threaded, for engagement with the cylinder walls of an internal combustion engine; a flange within said base adjacent one end thereof; a hollow shell in threaded engagement with the interior of said cylindrical base on the 65 end opposite said flange; an insulated member frictionally centered within said hollow shell having a shoulder thereon adapted to engage said base flange; a plural pointed flat electrode on said insulator end flush with the 70 end of said base; a cap housing adapted to center said insulated member within said hollow shell by engagement with said insulated member and hollow shell and a terminal nut for binding said hollow shell, insulated member and cap housing into an 75 integral unit.

In testimony whereof I have hereunto set my hand at San Francisco, California, this 14th day of November, 1919.

RAY L. HULL.

In presence of—

A. J. HENRY,

LINCOLN V. JOHNSON.
